UNITED STATES PATENT OFFICE.

GEORGE H. BLISS, OF PITTSFIELD, MASSACHUSETTS.

FASTENING DEVICE FOR BOOTS OR SHOES.

SPECIFICATION forming part of Letters Patent No. 334,738, dated January 26, 1886.

Application filed September 11, 1885. Serial No. 176,820. (No model.)

To all whom it may concern:

Be it known that I, GEORGE H. BLISS, of Pittsfield, county of Berkshire, and State of Massachusetts, have invented an Improvement 5 in Fastening Devices for Boots, Shoes, and other Articles, of which the following description, in connection with the accompanying drawings, is a specification, like letters on the drawings representing like parts.

10 This invention in button-fasteners is an improvement on that described in United States Patent No. 260,852, dated July 11, 1882, to which reference may be had. That patent shows and describes a fastener composed of a 15 plate to be fixed to a shoe, and a lever connected therewith and provided with a button, the said lever having at one end a cross-bar, which is placed in a slot of an ear of the plate, the said lever having a pivoted and also a sliding 20 movement, in order to permit the lever to turn when the button has been made to engage a button-hole, and also to permit the lever to slide horizontally, in order that it may engage a rigid hook carried by the plate. The but- 25 ton-carrying lever shown in the said patent is a rigid bar of metal, and to unbutton the shoe each lever has to be subjected to strain in such direction as to cause the lever to be moved bodily in the direction of its length, which at 30 times requires very considerable strain, and also makes it a slow process to unbutton the shoe.

To obviate the difficulties referred to, I have made the button-carrying lever as a spring, 35 and preferably of wire, the said lever having only a movement about its pivot or in the arc of a circle, the lever engaging a projection rising from the plate, the said projection being, however, of such shape as will permit the 40 button-carrying lever to be disengaged from it when the shoe is to be unbuttoned by a movement in the arc of a circle.

I have herein shown my invention as applied to a shoe.

45 My invention consists, essentially, in a fastener composed of an anchor-plate having a loop-like bearing and a catch or projection, combined with a spring-lever having an attached button or button-hole engaging pro- 50 jection, the said lever being pivoted at one end in the loop-like bearing, which latter holds the lever in manner substantially as will be here-

in after described, to obviate any extended lateral or longitudinal motion of the said lever.

Figure 1, in side elevation, represents a shoe 55 provided with my improved fastening devices, the overlapping portion or flap being partially open, to illustrate some of the fastening devices as fully operative in holding the said overlapping portion or flap, one fastening device being just inserted into a slit, but not turned back, other fastening devices being in readiness to be passed through the slits when the flap shall be further turned down. Fig. 2 is an enlarged side elevation of a fastening device 60 embodying my invention. Fig. 3 represents a side elevation, plan, and end view of the movable lever or portion of the fastening device detached; and Figs. 4 and 5 are modifications to be referred to. 70

The shoe A, having the top a and overlapping portion or flap a', (shown in Fig. 1 as provided with slits a''), are all of usual construction.

The anchor-plate c is herein shown as a short 75 piece of metal, having at or near one end a catch or projection, c'; and at its other end a loop-like bearing, c'', which serves as the pivotal point for the lever d, carrying the button or hook-like projection b, the said lever being 80 shown as composed of a piece of bent wire and moving in the arc of a circle, the loop-like bearing embracing one end of the wire 85 composing the said lever, acting not only to prevent longitudinal movement of the said lever, but also lateral movement thereof.

If the button-carrying lever should be held so loosely as to permit lateral movement thereof, difficulty would be experienced in causing the lever to correctly and unerringly engage 90 the catch or projection of the anchor-plate.

The lever d in Figs. 1 to 3, inclusive, is bent, as at d', to constitute a shank for the head of the fastening device, which head may be of any usual or suitable shape or material, the 95 said head being applied to the shank by casting or molding, or by pressure, as commonly practiced in button-making. The lever d is so bent or shaped, substantially as shown, that when turned down, as in dotted lines, Fig. 2, next 100 the anchor-plate, the said lever will engage the catch c', and be held or locked thereby in its backward or closed position.

The anchor-plate c is herein shown as at-

tached to the top or material *a* of the boot, shoe, or other article by rivets *e*, one rivet being shown as having a washer, *e'*, applied to it; but instead the anchor-plate may have 5 prongs of any usual construction to be inserted through the material and be clinched at the under side thereof.

The fastening device, having been attached to the top or material *a*, will be turned to occupy the position represented by the devices nearest the top of the shoe, and the person to button the shoe with the devices in such condition will cause the heads or projections *b* to engage or enter snugly the slits or eyes of the 10 overlapping portion or flap *a'*, as shown by the fifth fastening device from the top, and the head or projection appearing at the outside of the said flap will be engaged by the fingers, and so engaged the lever carrying the said 15 head or projection will be turned over (see Fig. 2) from the full into the dotted line position, thus straining or drawing the flap snugly down in place, closing the top of the boot or shoe about the foot, as represented by the 20 two lowermost fastening devices of Fig. 1.

In Fig. 4 I have shown a modification, wherein in the head or part, *b*, to enter the button-hole slit is composed of wire, and in said figure I have shown the catch *c'* as located at the end 25 of the anchor-plate, and the lever *d* is provided with a prolongation, *b''*, to co-operate with the said catch.

In Fig. 5 the free end of lever *d* is bent to form a head, *b*, shaped to resemble a hook, 30 the latter being shaped to readily engage or enter an eye, *a''*, located at the under side of the overlapping portion or flap *a*, part of which overlapping portion and an eye are shown in Fig. 5 near the said lever.

40 In case the fastening device is made as shown

in Fig. 5, the hook may be made to enter an eye made either as a loop of thread, or the eye may be made as part of a wire sewed between the two plies of the usual overlapping portions, and the latter at its upper side may 45 have, if desired, a series of false buttons added to it.

I claim—

1. The herein-described fastener, composed of an anchor-plate having the catch or projection *c'* and the loop-like bearing *c''*, combined with the spring-lever having an attached button or projection and pivoted with relation to the anchor-plate, one end of the said lever being embraced snugly by the said loop-like 50 bearing, whereby the lever, held in manner substantially as described, is prevented from undue lateral and longitudinal motion, as set forth.

2. The combination, with the anchor-plate 60 having one end upturned to form a loop-like bearing, *c''*, and having a catch or projection, *c'*, of a lever, *d*, composed of wire, extended through the said loop-like bearing and held therein snugly, the opposite end of the said 65 lever being provided with a button or projection, and being adapted to spring down over and engage the projection *c'*, all substantially as shown and described, the catch or projection being shaped substantially as shown, 70 whereby the lever may be disengaged from it without longitudinal motion of the lever with relation to the anchor-plate.

In testimony whereof I have signed my name to this specification in the presence of two sub- 75 scribing witnesses.

GEORGE H. BLISS.
